(57) **CLAIM**

The ornamental design for a device for cooking eggs with steam, as shown and described.

DESCRIPTION

FIG. 1 is a perspective view of the top, front and left side of a device for cooking eggs with steam showing my new design;

FIG. 2 is a left side elevational view thereof, the right side being a mirror image thereof;

FIG. 3 is a top plan view thereof;

FIG. 4 is a rear elevational view thereof;

FIG. 5 is a perspective view of the top, rear and right side thereof;

FIG. 6 is a bottom plan view thereof; and,

FIG. 7 is a front elevational view thereof.
